UNITED STATES PATENT OFFICE.

LEWIS F. TRULLINGER, OF LINCOLN, NEBRASKA, ASSIGNOR TO BERT TRULLINGER, OF LINCOLN, NEBRASKA.

LUBRICATOR FOR STEAM AND OTHER ENGINES.

1,098,995.

Specification of Letters Patent. Patented June 2, 1914.

Application filed March 18, 1913. Serial No. 755,242.

To all whom it may concern:

Be it known that I, LEWIS F. TRULLINGER, a citizen of the United States, residing at Lincoln, in the county of Lancaster and 5 State of Nebraska, have invented new and useful Improvements in Lubricators for Steam and other Engines, of which the following is a specification.

This invention is an improved lubricator 10 especially adapted for use in connection with a steam or other type of engine and also for use on machinery of various kinds for forcing lubricant to the parts required against the steam pressure of the boiler, the invention 15 consisting in the construction, combination and arrangement of devices hereinafter described and claimed.

In the accompanying drawings: Figure 1 is a vertical longitudinal sectional view of a 20 lubricator constructed in accordance with my invention, showing the same in use on the cylinder of a steam engine and arranged with its plunger for operation by the piston of the engine. Fig. 2 is a detail transverse 25 sectional view on the plane indicated by the line *a—a* of Fig. 1.

In the embodiment of the invention here shown, I provide a base plate 1 which is adapted to be secured on one side of the engine cylinder 2 at one end thereof. This 30 base plate is provided at its outer end, with a guide 3 which is here shown as having a threaded stem that passes through an opening in the base plate and as clamped in place 35 on the base plate by a nut 4. The guide has a rectangular opening 5.

The pump barrel 6 is secured on the base plate 1 and has a longitudinal bore and is provided at its front end with a stuffing box 40 7 and at its rear end with a nipple 8 arranged for the attachment of a steam pipe 9. An oil cup 10 is mounted on one side of the pump barrel 6 as at 11 and an oil pipe 12 in the said cup extends through one side of the 45 pump barrel and communicates with the bore 13 of the pump barrel.

A plunger rod 14 fits and is adapted to reciprocate in the bore 13 of the pump barrel and is under cut at its inner end as at 15 so 50 as to provide an extended arm 16 which acts as a cut off for the inner end of the oil pipe 12. This plunger rod extends through and operates in the packing box and has an enlarged cross sectionally rectangular portion 55 17 which operates in the opening 5 of the

guide 3 and coacts with the said opening to prevent the plunger rod from turning.

The outer end of the plunger rod is screw-threaded as at 18 and a pair of washers 19 are spaced apart and adjustably held on the 60 threaded portion of the plunger rod by means of nuts 20 and jam nuts 21. These washers form tappets. The piston rod 22 of the engine is provided with a tappet arm 23 which projects therefrom, is operated 65 thereby and has an opening through which the plunger rod extends, this tappet arm being arranged between the tappet washers 19 so that the said tappet arm coacts with said tappet washers to impart reciprocating 70 motion to the plunger rod from the piston rod of the engine so that the plunger rod moves back and forth in the bore of the pump barrel 6.

At each outstroke of the plunger rod the inner end of the oil pipe 12 is uncovered by 75 the arm 16 of the plunger rod so that oil passes from the oil cup into the bore 13 of the pump barrel and at each instroke of the plunger rod the said arm first cuts off the oil 80 pipe and the plunger rod acts to force the lubricant, against the steam pressure to the required part for use. The steam pressure against the underside of the arm 16 forces the latter against the upper side of the bore 85 of the pump barrel and causes the plunger rod to effectually cut off the oil pipe and compensates for wear of the plunger rod. The stroke of the plunger rod can be regulated by adjusting the tappet washers 19 by 90 means of the nuts 20—21 as will be understood, so that the capacity of the lubricator can be varied as may be required.

I claim:

1. In a lubricator of the class described, 95 a barrel having a bore and an oil cup, an oil pipe leading from the cup to the bore of the barrel, a plunger rod operating in the bore of the barrel and having its inner end undercut and provided with an extended 100 arm forming a cut off for the inner end of the oil pipe, means to operate said plunger rod, means to prevent the plunger rod from turning.

2. A lubricator of the class described, 105 comprising a base, a guide mounted directly thereon, a pump barrel also mounted directly on the base and having a bore, an oil cup, an oil pipe leading from the oil cup to the bore of the pump barrel, a plunger rod 110

operating in the guide and also operating in the bore of the pump barrel, the said plunger rod being undercut at its inner end and provided with an extended arm forming a 5 cut off for the inner end of the oil pipe, the said plunger rod and guide having coacting means to prevent the plunger rod from turning, adjustable tappet elements on the plunger rod and a tappet arm for connection 10 with the piston rod of an engine and to op-

erate between the said tappet elements to impart reciprocating motion to the plunger rod.

In testimony whereof I affix my signature in presence of two witnesses.

LEWIS F. TRULLINGER.
